Primary Examiner—M. N. Pandozzi*Attorney, Agent, or Firm*—Dowrey & Associates[57] **CLAIM**

The ornamental design for a backpack stove stand, as shown and described.

DESCRIPTION

FIG. 1 is a top perspective view of a backpack stove stand with the stove, fuel tank, and fuel line shown in broken line; FIG. 2 is an enlarged top perspective view thereof without the broken lines;

FIG. 3 is a right side elevational view, the left side elevational view being a mirror image thereof;

FIG. 4 is a top plan view thereof;

FIG. 5 is a bottom plan view thereof;

FIG. 6 is a front elevational view thereof;

FIG. 7 is a rear elevational view thereof; and,

FIG. 8 is a cross sectional view taken along lines 8—8 of FIG. 4.
